WITNESS:

UNITED STATES PATENT OFFICE.

WILLIAM H. HOLLIS, OF GERMANTOWN, PENNSYLVANIA, ASSIGNOR OF ONE-HALF TO
DR. VIVIAN PINNOCK-BAILEY, OF PHILADELPHIA, PENNSYLVANIA.

WASHBASIN FOR AUTOMOBILES.

1,422,763.

Specification of Letters Patent. Patented July 11, 1922.

Application filed November 8, 1921. Serial No. 513,730.

To all whom it may concern:

Be it known that I, WILLIAM H. HOLLIS, a citizen of the United States, residing at Germantown, in the county of Philadelphia and State of Pennsylvania, have invented 5 new and useful Improvements in Wash-basins for Automobiles, of which the following is a specification.

This invention relates to wash basins or 10 lavatory reservoirs that may be attached to any model of automobile, the primary object of which is to provide a wash basin secured to the underface of the running board, said running board having an opening 15 therein through which access may be had to said basin, a door hinged to said running board adapted to form a closure for said opening to conceal the interior of the basin and form a part of the running 20 board when in a closed position.

A further object of my invention is to provide a lavatory of this character wherein in the water supply to be used in the basin thereof for washing purposes is stored in 25 a tank or receptacle supported on the chassis of the automobile, a pipe leading from said tank and communicating with the said basin to supply water thereto through a spigot or valve in said basin, a 30 plugged discharge outlet in the bottom of the basin to discharge the water onto the highway when used.

A still further object of my invention is to provide a novel lavatory of this character 35 provided with a storage tank for water, the supply thereto being effected by projecting a hose through an opening in the apron of the automobile into the capped opening of the supply tank, the other end 40 of the hose being in communication with the source of water supply, means carried on the inner face of said apron adjacent the opening therein to close said opening when the hose is removed.

45 Furthermore I have provided in a novel apparatus of this character unique lighting means on the underface of the hinged door to provide light in the night use of this basin. I also provide a mirror carrier on 50 the underface of said door, furthermore in the basin and supported on the side walls thereof are trays adapted to contain various toilet articles or medicaments for the convenience of the occupants of the automobile.

55 In the further disclosure of the invention

reference is to be had to the accompanying sheet of drawings constituting a part of this specification, and in which like characters of reference designate the same or corresponding parts in all the views.

Figure 1— is an elevation of my improved wash basin for automobiles with parts broken away or in section for a better understanding of the structure.

Figure 2— is a top plan view of the running board showing the device in the closed position.

Figure 3— is a similar view by illustrating the device in the open or operative position to give access to the wash basin; and,

Figure 4— is a vertical longitudinal section taken on the line 4—4 in Figure 1.

Referring more particularly to the views a broken fragmentary portion of a vehicle chassis is designated by the numeral 1 75 whilst the apron thereof is indicated by the numeral 2, said apron supporting the usual running board 3. This running board 3 has an opening 4 cut therein to give access to the wash basin 5 of my novel device, the 80 same being secured to the underface of the aforesaid running board 3 in any of the well known ways. The basin 5 comprises front and rear walls, 6 and 7 respectively, and end walls 8 and 9, said walls being 85 integral with each other and with the bottom 10 of the basin. The top of the basin 5 is open and is of substantially the same area as the aperture 4 in the running board 3. The end walls 8 and 9 are provided at 90 their upper portions with integral flanges 11 and said flanges are positioned against the under-surface of the running board 3 and are secured thereto by bolt and nut fastening devices or the like 12 which hold 95 the basin securely to the running board 3. Other suitable fastening means may be used but it is desirable not to have any part of said fastening means projecting above the upper face of the running board 3. A 100 cover 13 is hinged to the running board 3 and is adapted when in closed position to light flush with the upper face of the running board 3 and to this end it is conveniently supported on the shouldered edges 105 14 provided for the purpose around the aperture 4. A finger-eyelet 15 is conveniently provided on the upper outer face of the cover 13 to provide for its opening and closing relative to the running board 3. A 110

storage tank or receptacle 16 for water is conveniently supported from the chassis 1 by strap bands or other supporting members 17 bolted to the said chassis by bolts 18. Access to this tank or receptacle for filling purposes is provided by means of a filler cap 19 whilst a pipe 20 provides outlet connection therefrom which communicates with the aforesaid wash basin 5, the outlet of the pipe in the basin being controlled by a spigot 21 located on the rear wall 7 and near the upper edge of said basin 5. A discharge outlet 22 is provided in the bottom of the basin 5 and is under the control of a plug 23, the removal of said plug permitting the draining of the basin 5 on to the highway or other place where the vehicle may be at the time said basin is used.

20 Side trays 24, 25 are secured to the end walls 8 and 9 respectively, of the basin 5 and said trays are conveniently divided into compartments for the holding of various toilet articles or medicaments for the use 25 of the occupants of the automobile. The cover 13 is provided on its underface with an electric incandescent light 26 which may be arranged in circuit with the ordinary lighting circuit of the automobile, said light 30 providing for the use of the apparatus after dark. A mirror 27 may be conveniently inset into the underface of the cover 13 so that when the door is opened the person using the basin 5 may also have the use of 35 a mirror for completing his or her toilet. A bracket 28 conveniently secured to and depending from the chassis 1 and connecting with the basin 5 affords a bracing and additional supporting means therefor. The 40 apron 2 is provided with an opening 29 under the control of a closure plate 30, said closure plate being adapted to be swung on one side for the insertion of a tube into the filling cap when it is desired to replenish 45 the tank or receptacle 16 with a fresh supply of water and said closure plate 30 is conveniently operable by means of a finger hold 31.

A canvas or other suitable material bag 50 32 as indicated in Figure 1 by the dot-and-dash line may be attached beneath the basin 5 by means of hooks and eyes if deemed necessary whereby the used water can be drained thereinto for the purpose of replenishing the radiator supply.

From the foregoing description the use and advantages of my improved wash basin for automobiles will be clearly apparent without further explanation or description. 60 Whilst there has been shown and described one practical embodiment of my invention, it will be apparent that the same is susceptible of many detail changes and variations and the right is hereby reserved to

make such changes and variations as fairly lie within the scope of the appended claims.

Having described my invention, what I claim as new and desire to secure by Letters Patent is:

1. The combination with the running 70 board and chassis of an automobile of a lavatory basin, a cover for said lavatory basin adapted to seat in flush with the surface of said running board, means for supplying water to said lavatory basin, and 75 means associated with the running board apron whereby said reservoir may be replenished.

2. The combination with the running board and chassis of an automobile of a 80 wash basin, means for bracing said wash basin to the chassis, a hinged cover for said wash basin adapted to seat in flush with the surface of said running board, a reservoir for supplying water to said wash basin, 85 and means associated with the running board apron whereby said reservoir may be replenished.

3. The combination with the running board and chassis of an automobile of a 90 wash basin, means for bracing said wash basin to the chassis, a hinged cover for said wash basin adapted to seat in flush with the surface of said running board, a reservoir for supplying water to said wash basin, a 95 closable aperture in the running board apron through which the reservoir may be re-filled when desired, and toilet holding receptacles in said wash basin.

4. The combination with the running 100 board and chassis of an automobile of a wash basin, means for bracing said wash basin to the chassis, a hinged cover for said wash basin adapted to seat in flush with the surface of said running board, a reservoir 105 for supplying water to said wash basin, a closable aperture in the running board apron through which the reservoir may be re-filled when desired, toilet holding receptacles in 110 said wash basin, and a mirror on the underside of the wash basin cover.

5. The combination with the running board and chassis of an automobile of a wash basin, means for bracing said wash basin to the chassis, a hinged cover for said wash 115 basin adapted to seat in flush with the surface of said running board, a reservoir for supplying water to said wash basin, a closable aperture in the running board apron through which the reservoir may be 120 re-filled when desired, toilet holding receptacles in said wash basin, a mirror on the underside of the wash basin cover, and means whereby the wash basin and mirror may be illuminated after dark.

In testimony whereof I affix my signature.

WILLIAM H. HOLLIS.
